ATTORNEY

UNITED STATES PATENT OFFICE.

CARL BLASENDORFF, OF BERLIN, GERMANY.

PUMP.

SPECIFICATION forming part of Letters Patent No. 252,350, dated January 17, 1882.

Application filed June 25, 1881. (No model.)

To all whom it may concern:

Be it known that I, CARL BLASENDORFF, a resident of the city of Berlin, German Empire, have invented Improvements in Pumps, of which the following is a specification.

5 Figure 1 is a central longitudinal section of the auxiliary differential twin pump. Fig. 2 is a similar section of the double-acting main pump, with which the auxiliary pump may be connected. Fig. 3 is a section of a single-acting main pump provided with automatic cut-off valves.

15 The twin cylinder B comprises end cylinders of uniform diameter and a larger intermediate central cylinder. Two smaller pistons, *a a'*, move in the end cylinders, and a larger piston, *b*, in the intermediate cylinder. These pistons are arranged in axial line on a single rod. The end cylinders are provided with suction-pipes 20 *g g*, which extend to the water-source, and with suction-valves *f f*, and also with force-valves *f' f'*, which open communication by means of side channels with the central cylinder. Pipes *d d*, connecting the twin cylinder with the main cylinder, open into the former on either side of the intermediate piston.

25 The main cylinder A is shown as a double cylinder in Fig. 1 and as a single cylinder in Fig. 2. In the former case it is provided with two valve-openings communicating with the water conveying or discharge pipes, closed by two cut-off valves, *n n'*, which are connected to and operated by a single rod, *m*. This rod *m* extends parallel with the pump-piston rod *p*, 30 and passes through the eye of an adjustable arm, *o*, which projects from said piston-rod. It is provided with adjustable gages *o' o'*, by

means of which the movement of the cut-off valves is regulated.

One of the columns of water in the pipes *d d'* 40 operates alternately as a piston for actuating the auxiliary pump.

What is claimed as the invention is—

1. The combination of a double-acting main pump, an auxiliary differential twin pump having two suction and force valves and three pistons, and two pipes connecting the main and auxiliary pumps, substantially as described. 45

2. The combination of a double-acting main pump having double sliding cut-off valves, an auxiliary twin pump having two suction and force valves and three pistons, and two pipes connecting the main and auxiliary pumps, so arranged that the water in each pipe is caused to serve alternately as a regulating-weight to 50 the pistons, substantially as described. 55

3. The combination of a double-acting main pump having double sliding cut-off valves, a reciprocating rod for operating the valves connected to the main piston-rod, and provided with adjustable gages for regulating the valves, an auxiliary twin pump having two suction and force valves and three pistons, and two pipes connecting the main and auxiliary pumps, so arranged that the water in each pipe is caused to serve alternately as a regulating-weight to 60 the pistons, substantially as described. 65

In testimony whereof I have signed my name to this specification in the presence of two subscribing witnesses.

CARL BLASENDORFF.
